DESIGN FOR A DISPLAY TABLE

John Edward King, Needham, Mass., assignor to
Corning Glass Works, Corning, N. Y., a corpora-
tion of New York

Application March 23, 1942, Serial No. 106,275

Term of patent 14 years

To all whom it may concern:

Be it known that I, John Edward King, a citizen of the United States of America, residing at Needham, county of Norfolk, State of Massachusetts, have invented a new, original, and ornamental Design for a Display Table, of which the following is a specification, reference being had to the accompanying drawing, forming a part thereof.

Fig. 1 is a perspective view, and

Fig. 2 is a top plan view of a display table embodying my new design.

Both figures are shaded to show ground glass panels set into the upper surfaces of the component parts of the table. The back and end surfaces which are obscured in the perspective view are identical in design with the corresponding visible surfaces.

I claim:

The ornamental design for a display table, substantially as shown and described.

JOHN EDWARD KING.
